UNITED STATES PATENT OFFICE

WILLIAM E. WINE, OF TOLEDO, OHIO

CROSS-BEARER

Application filed June 4, 1928. Serial No. 282,782.

My invention relates to cross bearers for railway cars and it has for one of its objects the provision of improved means for rigidly tying together and bracing structural parts of the car construction.

A primary feature of the invention consists in constructing the cross bearer of substantially trapezoidal form and in providing it with means adapted to receive angular plates for tying the sides of the car thereto.

Another feature of the invention consists in providing the cross bearer with upper and lower members integrally connected adjacent their opposite ends by diagonally extending members, said last-named members being provided with means whereby plate-like members may be respectively secured thereto and to the sides of the car.

Another feature of the invention resides in combining with the cross bearer, plate-like members of substantially right triangular form for connecting the cross bearer and side sheets of the car, the edge of each of the plate members constituting the hypotenuse of the triangle being secured to the adjacent side sheet.

Other and more specific features of the invention residing in advantageous forms, combinations and relations of parts will hereinafter appear and be pointed out in the claims.

Referring to the drawings illustrating a preferred embodiment of the invention:

Figure 1 is a fragmentary transverse sectional view of a railway hopper car, the cross bearer and plate-like members being in elevation.

Figure 2 is a fragmentary enlarged side elevational view of the cross bearer.

Figure 3 is a plan view of the construction illustrated in Figure 2, the adjacent side sheet and plate-like member being shown in dotted lines.

Figure 4 is a bottom view of a portion of the construction illustrated in Figure 2.

Figure 5 is an end elevational view of the construction illustrated in Figure 2.

Figure 6 is a sectional view taken on line 6-6, Figure 2.

Figure 7 is a fragmentary sectional view taken on line 7-7, Figure 2.

Figure 8 is a fragmentary sectional view taken on line 8-8, Figure 2.

Figure 9 is a perspective view of one of the plate-like members.

Referring more particularly to the drawings 1 indicates the car center sill and 2 the car side sills. The center sill is preferably composed of two flanged beams connected by a top cover plate 9. Each side sill is preferably formed with oppositely projecting upper and lower substantially vertical flanges 53 and 55, respectively, connected by an intermediate inclined web portion 54. The car sides may advantageously be formed of a plurality of sheets 23 respectively secured along their lower edges to the upwardly projecting flanges 53 of the side sills. Adjacent their upper edges they are preferably secured to side top rails 4 which may be conveniently reinforced by brackets 5.

The cross bearer, generally designated by the reference numeral 6, is of truss formation having top and bottom chord members 12 and 7, respectively. The bottom chord member 7 preferably extends continuously from one side of the car to the other, while the top chord member 12 terminates inwardly of the car sides. Each of the chord members is preferably of T-section having a top flange and a stem or depending portion, the upper surface of the flange being cambered as at 19 so as not to retain portions of the lading as it is being discharged from the car through the drop doors (not shown) in the bottom thereof.

Adjacent their extremities the upper and lower chord members are connected by diagonally disposed strut members 11 which converge upwardly from the outer ends of the lower chord. Intermediate their ends the chords are preferably connected by the diagonal struts 13 which diverge upwardly from adjacent the central portion of the lower chord and intersect the upper chord adjacent the point of juncture of the latter with the struts 11. It will thus be seen that the cross bearer is of substantially trapezoidal form, the upper and lower chords constituting the

parallel sides thereof and the struts 11 constituting the non-parallel sides. Furthermore, the struts 13 divide the cross bearer into three triangularly shaped portions, two of the 5 triangles being respectively defined by the adjoining struts 11 and 13 and the adjacent portion of the lower chord, and the other triangle being formed by the struts 13 and the upper chord.

10 All of the strut members may be advantageously be formed with substantially vertical flanges disposed in the same plane as the stems or depending portions of the upper and lower chords and with flanges projecting in the 15 same direction and preferably being of the same width as the flanges of the chords. Thus it will be appreciated that since all of the vertically disposed flanges of the cross bearer are disposed in the same plane they 20 constitute continuations of each other thereby providing the bearer with what in effect constitutes apertured web portions. The marginal edges of the vertical flanges of the top chord member and struts may be conveniently enlarged as at 20 to form beads 25 to additionally rigidify the structure.

At its central portion the lower chord member is provided with a pocket 8 adapted to receive the center sill 1. The top of this pocket 30 is formed by the central portion of the lower chord member, the flange of which is preferably enlarged as at 15, and the spaced depending walls or flanges 28, which are provided with a plurality of apertures 29 for receiving rivets to rigidly connect them to opposite sides of the center sill. Intermediate the depending portions 28 the cross bearer is formed with oppositely projecting flanges 30 which respectively incline downwardly in opposite directions from the top 40 of the lower chord member to afford means for supporting a hood sheet 10 which overlies the top cover plate of the center sill to cause lading to readily pass on opposite 45 sides thereof. These flanges 30 are integrally connected to the central portion of the cross bearer by substantially vertical wall portions 56 which depend from the marginal edges of the flange of the lower chord.

50 Each end of the cross bearer is provided with portions adapted to be secured to the adjacent side sill. These end portions project on opposite sides of the stem of the lower chord member and each is formed with a substantially vertical portion 57 for attachment to the upper flange 53 of the sill, an inclined portion 58 engageable with the inclined web 54 of the side sill and a lower substantially vertical portion 59 for attachment 55 to the lower flange 55 of the sill.

To provide convenient means for supporting adjacent portions of the inclined floor of the car, such as the sheets, 25, the cross bearer is preferably integrally formed on opposite 65 sides of the center sill with a plurality of

flanged portions 24 and 27 which respectively diverge downwardly from the lower edge of the depending portion of the lower chord member on opposite sides thereof. The flanges 24 respectively project inwardly from the end portions which are secured to the side sills and the flanges 27 project outwardly from the depending wall portions 28. Thus the side edges of each of the sheets 25 may be supported by and secured to the flanges 24 and 27 while the upper edges of each preferably terminates in an upwardly projecting flange adapted to be secured to an adjacent portion of the depending or stem portion of the lower chord.

70 In order to brace the sides 23 of the car and rigidly tie them to the cross bearer a plurality of plate-like members 3 are preferably employed. Each of these members is preferably of triangular shape and in the present embodiment of the invention they are illustrated as being of substantially right-triangular form. The outer edge of each member or the edge thereof forming the hypotenuse of the triangle is formed with a marginal flange 46 adapted to be secured to the inner face of the adjacent side sheet 23 by rivets which pass through openings 47 in the flange. At its upper edge the flange 46 is formed with a plurality of offset portions 48, 49 and 50 so as to conform to and be secured to the adjacent side top rail 4 of the car.

75 To provide convenient means for attaching the plate-members to the cross bearer, the diagonal struts 11 are respectively formed with upstanding flanges 40. The plates are preferably secured to these flanges by rivets which pass through apertures 42 formed therein and instead of the plates being arranged so as to be overlappingly secured to the same side of the flanges they may advantageously be disposed so that the plate on one side of the car overlaps that face of the adjacent flange 40 which is opposite to the 80 face of the other flange overlapped by the other plate.

85 Since the bulging forces to which the car sides are subjected tend to rotate them outwardly about the points to which they are secured to the side sills, the rivets employed for connecting the cross bearer and plate-like members adjacent the inner edges of the latter are subjected to forces of greater magnitude than those adjacent the outer edges of the members. Therefore, to provide means whereby additional rivets may be employed between the cross bearer and the plate members adjacent the inner edges of the latter, the flanges 40 are preferably integrally formed with laterally offset portions 41 affording convenient portions to which the flanges 52 formed on the inner edges of the plates may be secured. These flanges may, if desired, gradually decrease in width toward 90

the apices of the plates. The offset portions 41 may be suitably reinforced by triangularly shaped ribs or gussets 31. In addition to serving as means for tying the car sides to the cross bearer it will be appreciated that the plate-like members function in the usual manner as the side stakes.

Projecting from the flanges 40 in a direction opposite to that in which the flanges 46 of the associated plates project therefrom, are the flanges 22 which are adapted to be secured to adjacent portions of the side sheets. Thus, in addition to being connected to the side sills, the cross bearer is connected to the side sheets of the car. Furthermore the portions of the flanges 40 adjacent the flanges 22 are preferably enlarged as at 21 so that a very rigid connection may be obtained between the outer ends of the cross bearer and adjoining parts of the car construction.

From the foregoing it will be perceived that a cross bearer has been devised which may be rigidly secured to adjacent portions of the car construction and that by arranging the strut members in the manner disclosed the bearer itself is of sufficient rigidity to adequately withstand the forces to which it may be subjected.

Having thus described my invention, what I claim as new and desire to secure by Letters Patent is:

1. A cross bearer for freight cars of substantially trapezoidal form, the nonparallel sides thereof being adapted to receive angular plates for tying the sides of the freight car to said cross bearer.

2. A cross bearer for freight cars of substantially trapezoidal form, the nonparallel sides thereof being respectively provided with flanges adapted to receive means for tying the sides of the car to the cross bearer.

3. A cross bearer for freight cars of substantially trapezoidal form, the said trapezoid being internally divided into three triangularly shaped portions, the nonparallel sides of the cross bearer being provided with up-standing flanges adapted to receive means for tying the sides of the freight car to the cross bearer.

4. A railway freight car having a cross bearer of substantially trapezoidal form adapted to be rigidly secured to the car center sill and side sills, and plate-like members respectively rigidly secured to the non-parallel sides of the cross bearer for tying the latter to the sides of the car.

5. A railway freight car having a cross bearer provided with upper and lower chord member, means respectively connecting said members adjacent their opposite ends, each of said means being provided with flanges, and members respectively secured to said flanges and the sides of the car.

6. A railway freight car having a cross bearer provided with upper and lower chord

members, said members being respectively integrally connected adjacent their opposite ends by diagonally extending members, said last-named members being fashioned with upstanding flanges, and substantially triangularly shaped plate-like members respectively secured to said flanges and the sides of the car.

7. A railway freight car having a cross bearer provided with top and bottom chord members connected by diagonally extending strut members, and triangularly-shaped plate-like members respectively rigidly secured to the said diagonal members and the sides of the car.

8. In a railway freight car, the combination with side sheets and side top rails, of a cross bearer provided with diagonally extending members, and triangularly-shaped plate-like members respectively secured to the diagonal members of the cross bearer, said plate-like members being also secured to the said side sheets and top rails.

9. In a railway car, the combination with side sheets, of a cross bearer having strut members converging upwardly from adjacent the ends thereof, and plate-like members respectively rigidly secured to said strut members and side sheets, said plate-like members decreasing in width toward the top of the side sheets.

10. In a railway car the combination with side sills, of side sheets attached to said sills, a cross bearer rigidly secured to said sills having members respectively extending upwardly and inwardly therefrom, and plate-like members respectively secured to the said members of the cross bearer and the side sheets.

11. In a railway car, the combination with side sheets, of a cross bearer and plate-like members of substantially right triangular form respectively connecting the side sheets and cross bearer, the edge of each of said plate members constituting the hypotenuse of the triangle being secured to the adjacent side sheet.

12. In a railway car, the combination with side sheets, of a cross bearer having diagonally extending members, and plate-like members of substantially right triangular form connecting the side sheets and the diagonal members of the cross bearer, the edge of each of said plate members constituting the hypotenuse of the triangle being secured to the adjacent side sheet.

13. In a railway car, the combination with side sills, of side sheets attached to said sills, a cross bearer rigidly secured to the sills having members respectively extending upwardly and inwardly therefrom, and plate-like members of substantially right triangular form connecting the side sheets and the diagonal members of the cross bearer, the edge of each of said plate members con-

stituting the hypotenuse of the triangle being secured to the adjacent side sheet.

14. A railway car having a cross bearer of truss formation provided with top and bottom chord members and diagonally extending strut members, and plate-like members respectively rigidly secured to the strut members and the car sides.

15. A railway car having a cross bearer of truss formation provided with top and bottom chord members and diagonally extending strut members, said strut members having upwardly projecting flanges, and flanged plate-like members respectively secured to the flanges of said strut members and the car sides.

16. A railway car having a cross bearer of truss formation provided with top and bottom chord members and diagonally extending strut members, the latter being fashioned with upstanding flanges respectively having laterally projecting portions, and flanged plate-like members respectively secured to the flanges and the offset portions thereof and to the car sides for connecting the latter and the diagonal strut members of the cross bearer.

17. A railway car having a cross bearer, and a plurality of triangularly shaped members respectively secured to the cross bearer and the car sides for bracing the latter, said members being secured to the cross bearer adjacent their inner edges in a plurality of intersecting planes.

18. In a railway freight car, the combination with side sills, of side sheets respectively connected adjacent their lower edges to the side sills, a cross bearer rigidly secured to the side sills, and plate-like members secured to the cross bearer and side sheets for bracing the latter, said plate members being disposed in substantially vertical planes and being secured to the side sheets adjacent their lower edges.

19. In a railway freight car, the combination with side sills, of side sheets respectively connected to said sills, a cross bearer rigidly secured to the side sills and being provided with portions extending upwardly from the latter at an acute angle to the side sheets, and plate-like members respectively disposed in the angle formed by said portions of the cross bearer and side sheets for bracing the latter.

20. In a railway freight car, the combination with side sills, of side sheets respectively secured to said sills, a cross bearer of truss formation rigidly secured to the side sills, said bearer having struts extending inwardly and upwardly from adjacent said sills at an angle to the side sheets, and plate-like members respectively disposed in the angle formed by said struts and side sheets for bracing the latter.

In testimony whereof I affix my signature.

65 WILLIAM E. WINE.
